CLAIM

The ornamental design for a baked item, as shown and described.

DESCRIPTION

FIG. 1 is a perspective view of a baked item showing my new design;

FIG. 2 is a top view thereof, which is the same as the bottom view thereof;

FIG. 3 is a front view thereof;

FIG. 4 is a rear view thereof; and,

FIG. 5 is a right side view thereof, which is a mirror image of the left side view thereof.
